(57) **CLAIM**

The ornamental design for a quiver hood with detachable faceplate, as shown and described.

DESCRIPTION

FIG. 1 is a perspective view of our new ornamental design for a quiver hood with detachable faceplate, shown with the faceplate attached;

FIG. 2 is a left-side plan view of the quiver hood with detachable faceplate shown in FIG. 1;

FIG. 3 is a right-side plan view of the quiver hood with detachable faceplate shown in FIG. 1;

FIG. 4 is a front-side plan view of the quiver hood with detachable faceplate shown in FIG. 1;

FIG. 5 is a back-side plan view of the quiver hood with detachable faceplate shown in FIG. 1;

FIG. 6 is a top plan view of the quiver hood with detachable faceplate shown in FIG. 1;

FIG. 7 is a perspective view of our new ornamental design for a quiver hood with detachable faceplate, shown with the faceplate detached;

FIG. 8 is a left-side plan view of the quiver hood with detachable faceplate shown in FIG. 7;

FIG. 9 is a right-side plan view of the quiver hood with detachable faceplate shown in FIG. 7;

FIG. 10 is a front-side plan view of the quiver hood with detachable faceplate shown in FIG. 7;

FIG. 11 is a back-side plan view of the quiver hood with detachable faceplate shown in FIG. 7; and,

FIG. 12 is a top plan view of the quiver hood with detachable faceplate shown in FIG. 7.

One illustrative embodiment is provided. The illustrated embodiment shows the structure of a quiver hood with detachable faceplate. The broken lines in the drawings are for illustrative purposes only and form no part of the claimed design.
